CLAIM

The ornamental design for a compact disc holder, as shown and described.

DESCRIPTION

FIG. 1 is a perspective view of a compact disc holder showing my design, it being understood that the broken lines are for illustrative purposes only and form no part of the claimed design;

FIG. 2 is a top plan view of the compact disc holder illustrated in FIG. 1; and,

FIG. 3 is a side view of the compact disc holder illustrated in FIG. 1, the side view being representative of all side, front and back views due to the symmetry of the present invention.

The bottom of the compact disk holder is flat and unornamented.
